Primary Examiner — Selina Sikder(74) *Attorney, Agent, or Firm* — Schwegman Lundberg & Woessner, P.A.(57) **CLAIM**

The ornamental design for a controller device, as shown and described.

DESCRIPTION

FIG. 1 is a top plan view of a controller device, showing our new design.

FIG. 2 is a bottom plan view of the controller device.

FIG. 3 is a right side elevation view of the controller device.

FIG. 4 is a left side elevation view of the controller device.

FIG. 5 is a front elevation view of the controller device.

FIG. 6 is a rear elevation view of the controller device.

FIG. 7 is a top-right-front isometric view of the controller device; and,

FIG. 8 is a bottom-left-rear isometric view of the controller device.

The shade lines show contour and not surface ornamentation.
